MANUFACTURE OF SHOES

Karl Kilburn, Boston, Mass., assignor to United
Shoe Machinery Corporation, Paterson, N. J.,
a corporation of New Jersey

Application July 16, 1934, Serial No. 735,329

12 Claims. (Cl. 12—142)

This invention relates to improvements in shoes and methods of shoemaking and is illustrated herein with special reference to the manufacture of shoes having flexible foreparts. The 5 invention relates also to improvements in insoles and methods of making them.

In order to provide for flexibility in the foreparts of shoes, it has been proposed heretofore to skeletonize an insole forwardly of the ball line

10 before the insole is applied to the last by removing the central portion of the forepart of the insole so as to provide a central opening therein surrounded by a rim or rand-like portion of insole material. In using such a skeletonized insole

15 in the manufacture of a shoe, after the upper has been lasted and secured to the narrow rim comprising the forepart of the insole the reaction of the tensioned upper tends to distort or displace outwardly the rim of the insole with the result that the lasted shape of the shoe is not

20 maintained. For the purpose of preventing such outward displacement of the forepart of a skeletonized outsole, it has further been proposed to lay a piece of reinforcing material over the central opening and secure it adhesively to the rim.

25 This, however, is not always effective to prevent outward displacement of the rim on account of the tendency of the reinforcing material to stretch. Moreover, due to the fact that the central portion of the forepart has been removed,

30 there is some tendency for the remaining rim portion at the forepart of the insole to be distorted or displaced inwardly by the action of the wipers of the lasting machine.

35 The present invention, considered in one aspect, consists in an insole having a two-ply forepart portion, one layer of which is divided by a cut perpendicular to its top and bottom surfaces into a central cut-out part and a surrounding

40 frame part and the other layer of which is secured in face-to-face relation to said cut-out part and said frame part by cement which remains viscous in use to hold said frame part and said cut-out part in their original relation to each

45 other during the lasting of a shoe upper over said insole unit while enabling said cut-out part to be subsequently removed. The presence of the central cut-out portion in its original relation to the rim portion and the fact that the adjacent

50 edge faces of the cut-out portion and the rim portion are disposed at right angles to the top and bottom faces of those parts insures against any possibility of inward displacement of the rand-like rim portion resulting, for example,

55 from the action of the toe wipers of the lasting

machine during the lasting of the upper. Moreover, the piece of reinforcing material, being cemented to the central cut-out portion as well as to the rim portion, is thereby rendered practically incapable of stretching independently of 5 the cut-out portion. Thus the reinforcing material serves more effectively to hold the rim portion against outward displacement due to the reaction of the lasted upper.

In the practice of my improved method of shoemaking, after the upper has been lasted and secured to the rim or frame portion of the insole the central cut-out portion or panel of the insole is removed, by stripping or peeling it from the reinforcing piece, and the margin of the upper is 10 trimmed, the trimming being preferably gaged from the inner edge of the rim portion to provide sufficient surplus of upper material for folding down so as to overlie the inner edge of the rim portion of the insole. Thereafter, this surplus 15 upper material is cemented to the inner edge of the rim portion and an outsole, having its margin recessed at its attaching side so as to form a central projection adapted to fit tightly into the opening within the folded-down surplus of the 20 upper, is laid in place and the marginal surfaces formed by the recessing operation are cemented to the overlasted portions of the upper, including the folded-down surplus of the latter. Thus, the 25 folded-down surplus of the upper is not only bent 30 at right angles to the portion which overlies the face of the insole rim and confined in that relation between the inner edge of the insole rim and the edge of the central projection upon the outsole, but it is cemented to as well as tightly 35 clamped between the opposed insole and outsole edges and thus the upper is securely held against any force tending to displace it from its original overlasted relation to the shoe bottom.

Considered in another aspect the present invention provides an improved method of making insoles which consists in cutting out the central portion of the forepart of an insole by cutting at right angles to the top and bottom faces of the insole, thereby producing a skeletonized forepart 45 consisting of a rand-like peripherally-extending member having its inner edge face disposed at right angles to its top and bottom faces and thereby producing also a central portion completely severed from said rand-like member and 50 having its edge face at right angles to its top and bottom faces, and attaching a sheet of reinforcing material to said central cut-out portion and to said rand-like member by means of cement 55 which remains viscous in use thereby temporarily

securing said parts in their original relation to each other in a manner rendering them capable of being later readily separated. Alternatively the insole may initially be split edgewise from its toe end to the vicinity of the ball to provide a relatively thin flap at the inner or last-engaging side of the insole and a relatively thick flap at the opposite side of the insole, the relatively thick flap may have its central portion separated from its marginal portion, and the central and marginal portions of the relatively thick flap may be temporarily secured in their original relation to each other by cementing them to the relatively thin flap.

15 Invention is also to be recognized as residing in the various features of shoe and insole construction hereinafter described and claimed.

The invention will be explained with reference to the accompanying drawing, in which

20 Fig. 1 is a perspective view, partially broken away, showing the upper or last-engaging side of an insole prepared in accordance with my invention;

25 Fig. 2 is a fragmentary sectional view illustrating one of the steps in my method of preparing the insole;

30 Fig. 3 is a perspective view of a shoe lasted over my novel insole, the overlasted margin of the upper having been trimmed and also roughened to prepare it for the reception of sole-attaching cement;

35 Fig. 4 is a cross-sectional view of the shoe shown in Fig. 3 illustrating the step of trimming the overlasted margin of the upper;

35 Fig. 5 is a perspective view of an outsole prepared for assembly with the shoe shown in Fig. 3;

40 Fig. 6 is a fragmentary cross-sectional view of the lasted shoe as it appears after the outsole has been attached;

40 Fig. 7 is a fragmentary cross-sectional view of the completed shoe; and

45 Fig. 8 is a perspective view of a portion of an insole prepared in accordance with a modification of my invention.

45 In the manufacture of shoes having flexible foreparts, in accordance with my invention, an insole 20 is prepared, as illustrated in Fig. 1, by having the central portion 22 of its forepart entirely separated from the marginal portion 24 by 50 a cut 26 extending through the insole from its top face to its bottom face, and at right angles to said faces, the cut 26, as shown, being substantially parallel to the edge of the sole and extending also across the ball line. This cutting operation, as illustrated in Fig. 2, may conveniently be performed by means of a die 28 arranged to cooperate with a cutting block 30 upon which the insole 20 is positioned. After the insole has been cut as described a piece of reinforcing material 32 55 (for example canvas) which has previously been cut to a shape corresponding to that of the forepart of the insole but of slightly smaller size, is temporarily secured by means of adhesive to the upper surface of the central cut-out portion 22 and the surrounding rand-like marginal or rim portion 24. Rubber cement or some other adhesive which remains viscous in use is employed for this purpose so that the parts temporarily secured together thereby may be later separated readily 60 as will be hereinafter explained.

70 Alternatively the insole may be prepared as illustrated in Fig. 8 by having its forepart split edgewise at least as far back as the ball line to form a relatively thin flap 36 at the inner or last-engaging side of the insole and a relatively thick

flap 38 at the outer side of the insole, and by having the central portion 220 of the flap 38 entirely separated from the marginal portion 240 of the flap 38 by a cut 260 extending entirely through the flap at right angles to the top and bottom faces thereof. In accordance with the method exemplified in Fig. 8 the central cut-out portion or panel 220 of the insole 200, without being removed from its original relation to the embracing rand-like marginal or frame portion 240, 10 is temporarily retained in that relation by means of the relatively thin flap 36 which, for that purpose, is secured to both the cut-out portion 220 and the marginal portion 240 by means of cement of such a nature as that hereinbefore 15 referred to so as to permit the subsequent peeling or stripping of the cut-out portion from the flap, as will be hereinafter explained.

The insole, whether prepared as illustrated by Fig. 1 or as illustrated by Fig. 8, is attached 20 to the bottom of a last, such as the last 40, and an upper 42 is assembled on the last and pulled over in the usual manner.

25 In the lasting operation cement is introduced between the plies of the upper 42 and between the lining of the upper and the rand-like marginal portion 24 (or 240) of the insole. The upper is then worked into lasted position and secured to the portion 24 (or 240) by means of staples 44 as illustrated in Figs. 3 and 4. The fact that the 30 central cut-out portion 22 (or 220) of the insole has not been removed but remains in its original relation to the marginal portion 24 (or 240) and the fact that the adjacent edge faces of the cut-out and marginal portions are disposed at right 35 angles to the top and bottom faces of those portions insures against any undesirable inward distortion or displacement of the marginal portion of the insole under the stress of the lasting operation. Furthermore, the fact that the piece of 40 reinforcing material 32 has been securely cemented to the cut-out portion 22 as well as to the surrounding marginal portion 24 (or, in the case of the insole shown in Fig. 8, the fact that the flap 36 has been cemented to the cut-out portion 220 45 and the surrounding marginal portion 240) insures that the reinforcing piece will be less liable to stretch as a result of any reaction of the upper after it has been lasted.

50 After the lasting operation has been completed, the central cut-out portion 22 (or 220) of the insole is removed by stripping it from the reinforcing piece 32 (or the flap 36) and the overlasted upper margin is trimmed to provide only sufficient surplus of upper material extending inwardly beyond the inner wall of the marginal or frame portion of the insole (as indicated at 45) to enable the surplus upper materials to be folded inwardly over the inner wall of the rim portion in such a manner that the trimmed edges of the 60 upper materials will be substantially flush with the inner surface of the insole margin. This trimming of the upper materials may conveniently be accomplished by means of two cooperating shear members 46 and 48 (Fig. 4), the shear member 48 being constructed and arranged to cooperate with the inner edge of the insole frame portion 24 to gage the location of the trimming cut. If the shoe is to have its outsole secured thereto by means of cement the overlasted margin of the 70 upper is roughened in a customary manner, as indicated at 50, to prepare it for the reception of sole-attaching cement. This roughing operation may advantageously be performed before the cut-out portion 22 has been removed and the upper 75

materials have been trimmed and while the surplus materials are supported by the cut-out portion of the insole. As shown, a shank stiffener 52 is attached to the insole by means of tacks 54.

5 As illustrated in Fig. 5, an outsole 56 is prepared for assembly with the shoe by having its margin recessed, as indicated at 58, to form in the center portion of the forepart of the outsole a projection 60 having a substantially perpendicular edge face corresponding in outline to that of the perpendicular inner edge of the frame portion 24 of the insole but being sufficiently smaller than the latter to allow the surplus edge portions 45 of the upper material to be received between the 10 outsole projection 60 and the rand-like marginal portion 24 of the forepart of the insole. If the outsole is to be permanently cement-attached to the overlasted margin of the outsole the margin of the outsole will be roughened in any well-known manner, as indicated at 62. Cement will 15 of course be applied to the overlasted upper margin and to the roughened margin of the outsole and allowed to dry and just before attachment the cement will be activated and the shoe and sole brought together and placed under pressure. In attaching the outsole the projection 60 is forced into the central opening in the forepart of the insole, thus bending the surplus upper material 45 against the inner edge of the marginal portion of the insole and clamping it between that edge and the adjacent edge of the outsole projection 60. Preferably cement is applied to the inner 20 edge of the marginal portion 24 of the insole or to the under surface of the surplus upper materials 45 before they are pressed together. Thus, not only is the surplus 45 of the upper materials bent at right angles to the portions which overlie the face of the insole but it is firmly clamped between and cemented to the opposed edge portions 25 of the insole margin 24 and the outsole projection 60. Consequently, the upper materials are securely held against any force tending to displace them from their original overlasted relation to the shoe bottom. While the outsole is being attached the substantially perpendicular edge face 30 of its projection 60 serves also, in cooperation with the perpendicular inner edge of the frame portion 24 of the insole, as a positioning means in gaging the location of the outsole relatively to the shoe. If desired, of course, the outsole may be attached by through-and-through stitches, 35 for example, lockstitches.

The invention having been described, what I claim as new and desire to secure by Letters Patent of the United States is:

1. That improvement in methods of making insoles which consists in cutting out the central portion of the forepart of an insole by cutting at right angles to the top and bottom faces of the 40 insole, thereby producing a skeletonized forepart consisting of a rand-like peripherally-extending member having its inner edge face disposed at right angles to its top and bottom faces and thereby producing also a central portion completely 45 severed from said rand-like member and having its edge face at right angles to its top and bottom faces, and attaching a sheet of reinforcing material to said central cut-out portion and to said rand-like member by means of cement which remains viscous in use thereby temporarily securing 50 said parts in their original relation to each other in a manner rendering them capable of being later rapidly separated.

2. That improvement in methods of making insoles which comprises splitting the forepart of an

insole from the toe to the vicinity of the ball line thereby providing two flaps integral with the rest of the insole, cutting out the central portion of one of said flaps, and temporarily securing said cut-out portion in its original relation to the remaining peripheral portion of said flap and to the rest of the insole by means of cement which remains viscous in use thereby enabling said cut-out portion to be subsequently removed from said peripheral portion.

3. As an article of manufacture, an insole having a two-ply forepart portion, one layer of which is divided by a cut perpendicular to its top and bottom surfaces into a central cut-out part and a surrounding frame part and the other layer of which is secured in face-to-face relation to said cut-out part and said frame part by cement which remains viscous in use to hold said frame part and said cut-out part in their original relation to each other during the lasting of a shoe upper over said insole unit while enabling said cut-out part to be subsequently removed.

4. An insole having an outline corresponding to that of the bottom of a last and having a central forepart portion cut out forwardly of the ball line, and means integral with the insole and secured to said cut-out portion by means of cement which remains viscous in use thereby facilitating the subsequent removal of said central forepart portion.

5. An insole comprising a sheet of material conforming in shape to a last bottom and having its forepart split from substantially the ball line forward to the toe thereby providing a relatively thin flap and a thicker flap, the central portion of the thicker flap being entirely severed from the rest of said flap to provide a central cut-out portion and a narrow rand-like member extending peripherally of the forepart of the insole forwardly of the ball line and of uniform thickness 40 throughout, the thin flap, the rand-like member, and said cut-out portion being temporarily secured in their original relation to each other by cement which remains viscous in use so that said cut-out portion may subsequently be readily 45 removed.

6. That improvement in methods of manufacturing shoes which comprises supplying an insole having its forepart split into two flaps, one of which comprises a central cut-out panel and an embracing frame portion and the other of which is temporarily secured to both said panel and said frame portion, assembling said insole and a shoe upper on a last, working the shoe upper into lasted relation to the insole and last and securing it in that position, removing said panel, trimming the marginal portion of the shoe upper so that it extends inwardly beyond the inner edge of said frame portion a distance substantially equal to the thickness of the insole, supplying an outsole having a forepart projection corresponding in shape and location to that of said panel but enough smaller to receive between it and said frame portion the inturned edge of the upper, and attaching said outsole to the shoe bottom with said projection filling the space formerly occupied by said panel and with the extreme edge of the upper turned in between said projection and said frame portion.

7. That improvement in methods of manufacturing shoes which comprises supplying an insole having a relatively thin forepart flap and a substantially thicker forepart flap, the latter comprising a central cut-out panel and an embracing frame portion and the former being temporarily

secured to both said panel and said frame portion, assembling said insole and a shoe upper on a last with said relatively thin flap in engagement with the last bottom, working the shoe upper into lasted relation to said frame portion and securing it thereto, thereafter removing said panel, supplying an outsole having a projecting forepart portion conforming in shape and location to said panel, and attaching said outsole to the shoe bottom with its projecting portion in place of said panel.

8. That improvement in methods of manufacturing shoes which comprises supplying an insole having a split forepart comprising a relatively thin flap and a substantially thicker flap, the latter having a central cut-out panel and an embracing frame portion and said relatively thin flap being temporarily secured to said panel and said frame to the adjacent marginal portion of said relatively thick flap portion by cement, assembling said insole and a shoe upper on a last with said relatively thin flap in engagement with the last bottom, working the shoe upper into lasted relation to the insole and last and securing it in lasted relation to the insole by fastenings passing into said frame portion, thereafter removing said panel, trimming the surplus material from the margin of the upper but leaving the overlasted marginal portion of the upper at least wide enough completely to cover said frame portion, supplying an outsole having a portion projecting from its attaching surface at the forepart, said projecting portion conforming in shape and location to said panel, and attaching said outsole to the shoe bottom so that its projecting portion takes the place of said panel.

9. That improvement in methods of manufacturing shoes which comprises supplying an insole having in its forepart a central cut-out panel and an embracing frame portion having a substantially perpendicular inner edge, assembling said insole together with its central panel with a shoe upper on a last, working the upper over the last and securing it in overlasted relation to the insole, removing said panel from the insole, trimming the surplus material from the overlasted margin of the upper along a line substantially parallel to the inner edge of said frame portion and spaced therefrom a distance substantially equal to the thickness of said frame portion, supplying an outsole having a project-

ing portion the margin of which is defined by a substantially perpendicular shoulder of a contour complementary to that of the inner edge of said frame member, and applying said outsole to the shoe thereby clamping the inwardly extending trimmed edge of the upper between said shoulder and the inner edge of said frame portion, and utilizing said shoulder as a positioning means in gaging the location of the outsole relatively to the shoe.

10. A shoe comprising an insole the forward portion of which consists only of peripherally-extending, rand-like member having a substantially perpendicular inner edge portion, an outsole formed with a projection at the forepart of its attaching face received by the cut-out of the insole, said projecting portion having a substantially perpendicular edge portion spaced from the inner edge portion of said rand-like member, and a shoe upper having its margin filling the space between said edge portions.

11. A shoe comprising an insole the forward portion of which consists only of a peripherally-extending, rand-like member the inner edge of which is formed by a cut substantially at right angles to the surface of the insole, an outsole formed with a projection at the forepart of its attaching face corresponding in shape with and received by the cut-out of the insole, said projection having a peripheral edge substantially at right angles to the surface of the outsole, and an upper overlasted upon and secured to the face of said rand-like member, the inner marginal portion of the upper extending between the inner edge of said rand-like member and the peripheral edge face of said projection on the outsole and secured by adhesive to those edges.

12. That improvement in methods of making insole units having two-ply foreparts which consists in cutting out the central portion of an insole forepart layer at right angles to the top and bottom surfaces of said layer, and attaching a second insole layer to the cut-out portion and to the surrounding portion of said first layer by means of cement which remains viscous in use, thereby enabling said cut-out portion to be readily removed from said surrounding portion after a shoe upper has been secured in overlasted position to the latter.
